UNITED STATES PATENT OFFICE.

WILLIAM COCHRANE, OF EAST WOODSTOCK, CONNECTICUT.

COVER-FASTENER FOR FRUIT-JARS.

SPECIFICATION forming part of Letters Patent No. 276,670, dated May 1, 1883.

Application filed March 10, 1883. (Model.)

To all whom it may concern:

Be it known that I, WILLIAM COCHRANE, a citizen of the United States, residing at East Woodstock, in the county of Windham and State of Connecticut, have invented certain new and useful Improvements in Cover-Fasteners for Fruit-Jars; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention consists in a fastener for a fruit-jar cover, formed of a coiled spring, heads respectively at the top and bottom of the coiled spring, and hooks or claws reaching down from the upper head on opposite sides of the 20 spring and adapted to catch under ears or a flange on the neck of the jar, substantially as hereinafter specified.

In the accompanying drawings, Figure 1 represents a side view of one of the spring-fasteners; Fig. 2, a top view of the same; Fig. 3, a top view of a modified construction thereof; Fig. 3^a, a side view of the same; Fig. 3^b, another side view at right angles to the first side view thereof; Fig. 4, a side view of the fruit-jar with one of the fasteners in position on its cover prior to compressing and securing the same; Fig. 5, a side view of the jar after the fastener has been compressed and secured in place.

35 Like letters designate corresponding parts in all of the figures.

The fastener A is formed as a coiled spring, substantially as shown in Fig. 1. At the respective ends of the spring are heads a b. 40 These heads may be sheet-metal plates or disks attached to the spring, as shown in Fig. 2; or they may be portions of the same wire which forms the spring, as shown in Figs. 3, 3^a, and 3^b, where the lower head is formed of the 45 last or largest coil of the spring and the upper head is in the form of a cross-bar made of the upper part of the spring-wire. From the upper head or disk, a, of the fastener project downward hooks or claws c c, respectively, on 50 opposite edges of the same. These hooks or

claws are formed to take and hold under the ears or flange d d, usually formed on the neck of a fruit-jar, B. They may be attached in any suitable way to the head a, if the latter is formed of sheet metal, or as a disk of any material, as shown in Figs. 1 and 2; or, if the head is of wire, the hooks or claws may be continuations of the wire forming the said head, as shown in Figs. 3, 3^a, and 3^b, wherein the upper part of the spring is represented as 55 first extended outward, then downward, and then inward, as at x, then outward, upward, and inward, as at y, by the side of the part x, then outward to the opposite side of the spring, then downward, and then inward, as at z, where 60 the wire terminates.

As seen in Fig. 4, when the fastener is placed in position, with its lower head resting on the cover of the jar B, the hooks or claws c c do not reach down to the neck of the jar, so that 70 the spring A has to be compressed before the hooks or claws can hook under the ears or flange of the neck of the jar, as indicated in Fig. 5. The parts are to be so proportioned that the requisite compression of the spring 75 on the jar-cover is produced when the hooks or claws are secured under the ears or flange of the jar-neck.

This fastener is very secure, the bearing of the lower head thereof on the jar-cover being 80 broad and the pressure equal all around from the spring above; and the fastening cannot get loose nor fail to hold the jar-cover at all times. It is also very easily applied and taken off and readily adjusted to the right position. It is 85 cheaply made, and is very durable, not being liable to break, get out of order, or wear out.

What I claim as my invention, and desire to secure by Letters Patent, is—

A fastener for a fruit-jar cover formed of a 90 coiled spring, A, heads a b, and hooks or claws c c, and adapted to be applied to a fruit-jar, substantially as and for the purpose herein specified.

In testimony whereof I affix my signature in 95 presence of two witnesses.

WILLIAM COCHRANE.
